GRASS TRIMMER

Jack J. Zimmerman, Riverside, Ill., assignor to Phonex
Instrument Company, Inc., Chicago, Ill., a corporation

Filed Feb. 21, 1961, Ser. No. 64,014

Term of patent 14 years

(Cl. D40—1)

FIGURE 1 is a side elevational view of a grass trimmer embodying my new design;

FIGURE 2 is a front elevational view thereof;

FIGURE 3 is a top plan view thereof; and

FIGURE 4 is a bottom plan view thereof.

The stippling on the handle represents contrasting surface areas.

I claim:

The ornamental design for a grass trimmer, substantially as shown and described.
